UNITED STATES PATENT OFFICE.

THOMAS J. KELLEHER, OF CHICAGO, ILLINOIS.

BENDING BRAKE.

Application filed April 16, 1924. Serial No. 706,896.

To all whom it may concern:

Be it known that I, THOMAS J. KELLEHER, a citizen of the United States, and a resident of Chicago, in the county of Cook and State of Illinois, have invented certain new and useful Improvements in Bending Brakes, of which the following, reference being had to the drawings accompanying and forming a part hereof, is a specification.

10 This invention relates to bending brakes by means of which sheet metal of slight and of considerable thickness is bent or folded.

Among the objects of the invention are to lessen the number of parts and the cost 15 of a bending brake having determined strength and rigidity; to obtain a brake of the kind named which is durable and not liable to get out of order, or to become broken, and which is easily adjusted to 20 bend different thicknesses of metal; to obtain a brake by means of which a portion of a sheet of metal may be bent, to at least ninety degrees, and the remainder of said sheet will not be bent or folded; and a 25 brake which is easily understood and operated by men skilled in the art of bending sheet and bar metal.

In the drawings referred to and illustrating the invention, Figure 1 is an end elevation 30 of a bending brake embodying the invention;

Fig. 2 is a central vertical section of the brake which is illustrated in Fig. 1;

Fig. 3 is a front elevation of the bending 35 leaf or apron of the brake, removed from the remainder thereof;

Fig. 4 is a top plan view of a sheet metal plate or blank from which the inclined member and part of the ends of the upper member of the jaw of the brake is obtained;

Fig. 5 is a top plan view of the sheet metal plate or blank from which the horizontal member and part of the ends of the upper member of the jaw of the brake is obtained;

Fig. 6 is a top plan view of the sheet metal plate or blank from which the horizontal member of the bed and part of the ends of the brake is obtained;

Fig. 7 is a top plan view of the sheet metal plate or blank from which the vertical supporting member to the forward side of the bed of the brake, and part of the ends of the end of the bed of the brake is obtained, and

Fig. 8 is a vertical section of one end of the movable upper member of the jaw and

of the bed of the brake on line 8—8 of Fig. 2, viewed as indicated by arrows.

A reference character applied to designate a given part indicates said part throughout 60 the several figures of the drawings wherever the same appears.

1. Fig. 4, represents a sheet metal blank, which is folded or bent on broken lines 2, 2 to obtain portions or parts 3, 3 of the 65 respective ends of the upper member of the jaw of the brake and the inclined table 4. 5, Fig. 5, represents a sheet metal blank which is folded or bent on broken lines 6, 6 to obtain portions or parts 7, 7 of the respective ends of the upper member of the jaw of the brake and horizontal table 8. 9, Fig. 6, represents a sheet metal plate or blank, which is folded or bent on broken lines 10, 10 to obtain portions or parts 11, 11 of the respective ends of the horizontal member 12 of the bed of the brake and the projecting side or edge 13 of said horizontal member. 14, Fig. 7, represents a sheet metal plate or blank which is folded or 70 bent on broken lines 15, 15 to obtain parts or portions 16, 16 of the respective ends of the vertical member 17 of the bed of the brake. 18, 18 respectively represent slots in blank 14, which permit the upper portion 75 19, Figs. 1 and 2, of the vertical member 17 to be curved or bent toward the forward edge of horizontal member 12 of the bed of the brake.

19, 19, represent metal rods welded to 90 said portion 19 and to horizontal member 12.

The several bends of blanks 1, 5, 9 and 14, on the lines 2, 2, 6, 6, 10, 10 and 15, 15, respectively, are right angle bends, bringing the parts 3, 3 of blank 1, parts 7, 7 of 95 blank 5, parts 11, 11 of blank 9, and parts 16, 16 of blank 14, into planes which are at right angles to the body parts 4, 8, 12 and 17, respectively.

20 represents the thrust receiving bar of 100 the upper member of the jaw of the brake, which is rigidly secured to the horizontal member or table 8, as by metal rods 21, 22, which are welded to said table 8 and to said bar. Said bar 20 is also rigidly joined to 105 inclined table or plate 4 of the upper member of the jaw of the brake by metal rod 23 which is welded to said inclined table 4 and to said bar 20 (see Fig. 2). 24, Figs. 1 and 2, represents a bar which is bent to obtain 110 a horizontal and a vertical portion. The horizontal portion of said bar 24 is rigidly

secured to the under side or face of horizontal member 12 of the bed of the brake, as by metal rod 25 which is welded to said bar and to said horizontal table. Said bar 24 is also illustrated in Fig. 2 as rigidly attached to the horizontal member 12 by the rod 26, which is welded to said horizontal member 12 and to the vertical part of said bar 24. 24^a represents a bar which is rigidly secured to the horizontal member 12 at the forward side thereof, to form the lower member of the jaw of the brake, and secured thereto by metal rods 24^b, 24^b, which are welded to said bar and horizontal member.

15 The vertical part of bar 24 extends upward above the horizontal table 8 of the upper member of the jaw of the brake, to prevent backward movement of said upper member of the jaw when a bar or a sheet of metal is forced against the thrust receiving bar 20 by the pivotal movement of the bending leaf or apron of the brake.

25 27, 27 represent, respectively, bars which are rigidly secured to the ends of the bed of the brake, as by spot welding (or rivets) 28, 28. Bars 27, 27 are projected beyond the inclined table 4 and the thrust receiving bar 20 of the upper member of the jaw of the brake, to obtain supporting members of the pivots 29, 29. 30, 31 represent legs which form the supports for the bed of the brake. 32, 32 represent base members to which the lower ends of legs 30, 31 are respectively secured; and 33, 33 represent diagonally extending braces which are rigidly secured, as by rivets 34, 34, to said legs 30, 31 and said base members 32, 32.

30 40 The ends 3, 7 and 3, 7 at the two ends of the upper member of the jaw of the brake are rigidly joined, as by spot welding (or rivets) 34^a, 34^a and form the head of said upper jaw member. The ends 11, 16, 11, 16 of the blanks 9 and 14 are respectively rigidly joined together as by spot welding (or rivets) 34^b, 34^b, to form the heads of the bed of the brake; and said heads are rigidly joined to legs 30, 31, as by spot welding (or rivets) 34^c, 34^c.

45 50 The bending leaf or apron of the brake comprises the channel iron 35, which extends the entire length of said bending leaf, and the U-shaped members 36, 36, which are pivotally mounted on bolts or pivots 29, 29, said bolts or pivots also extending through the bars 27, 27.

55 57, 37 represent bolts which are screw threaded at their lower ends, respectively, as at 38, 38, Figs. 1, 2 and 3, and are respectively provided with a nut 39 having corresponding screw threads therein. 40 represents the head of a bolt 37. Opposite sides of said head 40 are removed, or cut away, so that said head fits in the U-shaped member 36 (see Fig. 3), and said bolt is thereby prevented from turning.

41, 42, 43 and 44 respectively represent thrust receiving members, which are illustrated as angle irons, which are respectively rigidly secured to the upper side of the web 35^a, Figs. 1 and 2, of channel iron 35, as by 70 bolts 45, 45. Upon the removal of one or more of these thrust receiving members 41, 42, 43 and 44 from said channel iron web, a corresponding portion of a sheet of metal held rigidly by the jaws of the brake will 75 not be bent or folded, while the portion of said sheet of metal against which the unremoved one, or ones, of said members are forced, will be bent.

The making of the thrust member of the 80 folding leaf in a plurality of parts is to enable the brake to be used in what is known in the trade as special work.

The adjustments required to bend or fold different thicknesses of sheet metal, at different times, is obtained by me by turning the nuts 39, 39 on screw threads 38, 38 on bolts 37, 37, thereby varying the distance of channel iron 35 from pivots 29, 29, and so varying the diameter of the path of travel 90 of the thrusting edge of the members 41, 42, 43 and 44.

46, 46, Figs. 1 and 2, indicate by broken lines angle irons which may be secured by bolts 47, 47 to members 41, 42, 43 and 44, or to any one thereof when desired. Said angle irons 46, 46 are ordinarily used in certain work and form no part of my invention.

The upper member of the jaw of the 100 brake is forced down on to the sheet metal or bar placed between the thrust receiving bar 20 and the bar 24^a in the ordinary way, as by an eccentric mounted on pivots 48, 48, links 49, 49, pins 50, 50 and handles 51, 51, and form no part of my invention.

52, 52 represent sockets at the ends of the bending or folding leaf. 53, 53 represent rods in said sockets, and 54, 54 counter weights on said rods.

I claim:

1. In a bending brake, a bed provided with ends integral therewith, bars rigidly secured to said ends and extending forward thereof, and pivots in said extended ends, in combination with a folding leaf comprising U-shaped members mounted on said pivots, bolts non-rotatably extended through the horizontal bar of said U-shaped members respectively, a channel iron mounted on said bolts, and nuts on the lower and screw-threaded ends of said bolts, adapted to determine the position of said channel iron relative to said pivots.

2. In a bending brake, a bed provided with heads integral therewith, bars rigidly secured to said heads and extending forward thereof, additional bars rigidly secured to said bed, with the ends of said additional bars extending vertically above the upper face of said bed, and a bar rigidly secured

to the forward side of said bed, in combination with a movable member forming the upper member of the jaw of the brake and comprising an inclined table and a horizontal table, the ends of said tables at right angles to the body parts thereof and rigidly joined to form the heads of said jaw member, and said horizontal table adapted to be forced against said vertically extending portions of said additional bars.

3. In a bending brake, a folding leaf comprising pivotally mounted U-shaped members, provided with horizontal bars joining the parallel elements thereof, bolts non-rotatably extending through the horizontal bar of said U-shaped members respectively, a channel iron mounted on said bolts, and nuts on the lower and screw-threaded ends

of said bolts, to control the position of said channel iron relative to said pivots, all combined as set forth. 20

4. In a bending brake, a folding leaf comprising, in combination, pivotally mounted U-shaped members, bolts non-rotatably mounted on said U-shaped members, said bolts screw-threaded on the lower ends thereof, a channel iron mounted on said bolts, and nuts on the lower screw-threaded ends of said bolts, to control the position of said channel iron relative to the pivots on which said U-shaped members are mounted, 25 a plurality of thrust receiving members mounted on said channel iron, and means to secure said thrust receiving members to said channel iron. 30

THOMAS J. KELLEHER.
